CRIB END

Robert V. Jacobs and Allen D. Jacobs, Los Angeles,
Calif., assignors to Questor Corporation

Filed July 24, 1972, Ser. No. 274,349

Term of patent 14 years

Int. Cl. D6—01

U.S. Cl. D6—14

FIG. 1 is a top plan view of a crib end showing our new design;

FIG. 2 is a front elevational view; and

FIG. 3 is a right side elevational view.

The opposite side of the panel shown in FIG. 1 is plain and unornamented.

We claim:

The ornamental design for a crib end, as shown.
